UNITED STATES PATENT OFFICE.

HEINRICH LOUIS KARGER, OF BERLIN, GERMANY, ASSIGNOR TO SELAS GESELLSCHAFT MIT BESCHRÄNKTER HAFTUNG, OF BERLIN, GERMANY.

APPARATUS FOR MIXING AIR AND GAS FOR ILLUMINATING PURPOSES.

No. 797,361.

Specification of Letters Patent.

Patented Aug. 15, 1905.

Application filed July 7, 1903. Serial No. 164,538.

To all whom it may concern:

Be it known that I, HEINRICH LOUIS KARGER, engineer, a subject of the Emperor of Germany, residing at 26 Frankfurter Allee, Berlin, in the Empire of Germany, have invented certain new and useful Improvements in Apparatus for Mixing Air and Gas for Illuminating Purposes, of which the following is a specification.

It is already known in illuminating installations in which the increased gas-pressure is obtained by means of a motor in constant operation to regulate the pressure by the arrangement of a circulation-conduit. Hitherto such circulation-conduits have been employed only in installations in which one kind of gas only has been placed under a high pressure. In accordance with this invention uninterrupted operation is provided for by means of circulation-conduits in appliances for mixing gas and air and also for the supply of the mixture at a high pressure, so that in this case both air and gas or two different kinds of gas are sucked in and forced out. The suction of the two kinds of gases may be effected either into a common chamber or into separate chambers. The employment of a special circulation-pipe for gas and another for air is not possible, because exact coöperation of the valves leading back to the pressure-main is unattainable.

In order that both kinds of gas may retain the mixing proportions originally decided upon, it is essential in accordance with this invention that the same excess-pressure valve should cause the obturation of the gas-supply pipe and also at the same time that of the air-supply pipe by the transmission of the pressure, while at the same time communication is established between the suction-chamber and the forcing-chamber or with the service-main. When this is the case, the suction and forcing of air and gas no longer takes place, but the suction and forcing of a mixture of gas and air from the pressure-chambers through the common valve into the circulation-pipe. Provision must not only be made for the simultaneous obturation of the supply-valves for the gas and air, however, but also that under normal conditions, when the circulation-pipe is inoperative, the gas shall not be able to pass to the air-conduit. This may be effected by the arrangement of special non-return valves between the gas-conduit and the air-conduit

or by the special manner of placing the suction-valves for gas and air in the circulation-conduit so that they coöperate. After the obturation of the gas-conduit and of the air-conduit has been effected it is possible, as shown in the various constructional forms illustrated, for the suction of the gas-and-air mixture into the forcing-chamber of the suction and forcing device to take place either through the gas-supply valve or through the air-supply valve, or through both. This latter is advantageous, because an increase of resistance in the suction and forcing apparatus is obviated, which would otherwise take place if after the circulation-pipe were rendered operative the whole of the gas-and-air mixture to be supplied had to pass through one only of the suction-valves.

A further improvement consists in the fact that the air-suction valve also serves as a non-return valve. In this case the special valve which would otherwise be necessary for obturating the air-supply pipe is not required.

The resistance during the suction of the gas-and-air mixture may also be still further diminished, owing to the fact that the circulation-conduit is directly connected with the operative chamber of the suction and forcing apparatus. In this case there is arranged in front of the obturating members which cut off the admission of gas and air a special non-return valve, which normally works idle, but which when the circulation-pipe is operative is maintained closed by the excess pressure, and thereby cuts off the supply of gas and air. This arrangement is especially advantageous in the case of link-motion or positively-operated gas and air admission organs.

The invention is illustrated in the accompanying drawings, in which—

Figure 1 illustrates the construction of an apparatus for producing a mixture of gas and air by means of separate suction and forcing appliances. Figs. 2 to 5 show various constructional forms with only one suction and forcing appliance for supplying both gas and air. Figs. 6 to 8 illustrate different arrangements of valves upon a larger scale.

In the constructional form represented in Fig. 1 the suction and forcing appliance 1 serves for the gas and the suction and forcing appliance 2 for air. The appliance 1 is provided with a gas-suction valve 3, connected to the gas-conduit 4, and with a forcing-

valve 5, which is connected to the gas-pressure conduit 6. In the gas-supply pipe is mounted a non-return valve 7, which opens in the direction of the suction-valve 3 under the gas-pressure. The air suction and forcing appliance 2 is provided with the air-suction valve 8 and the forcing-valve 10. The valve 8 is in communication with the air-supply pipe 9. The air-pressure conduit is connected to the valve 10. In the air-supply pipe 9 is mounted a non-return valve 12, which opens in the direction of the suction-valve 8. The two conduits 6 and 11 unite, so as to form the pressure-pipe 13, which leads to a pressure-reservoir, gasometer, or the like 14 for the reception of the mixture of gas and air, from which latter the service-pipe 15 leads. The pipe 13 may also serve directly as the service-pipe.

The conduit 16 is directly connected to the reservoir 14, or it may be connected, by means of a pipe 22, with the pressure-pipe 13. The conduit 18 leads to the conduit-section 20 of the gas-supply pipe 4, lying between the non-return valve 7 and the gas-suction valve 3, and the conduit 19, also connected to the conduit 16, leads to the portion 21 of the air-supply pipe 9 between the non-return valve 12 and the air-suction valve 8. In the branch 18 of the circulation-conduit is mounted a non-return valve 23^a, which opens in the direction of the pipe-section 20. This valve serves to prevent the passage of gas from the gas-pipe 4 into the pipes 18 19, and thus into the air-supply pipe. In the same manner a non-return valve 23 may be arranged in the branch 19.

In the conduit 16 is arranged an excess-pressure valve 17, which is adapted for adjustment to various pressures. The excess-pressure valve here represented is provided with a membrane 56, which carries the obturating-body 17. This valve is constructed in such a manner that it opens when excess pressure acts in the direction of the arrow *a* from the reservoir 14 on the membrane 56. The operation of this installation is as follows: By means of the suction and forcing devices 1 2 gas and air are sucked through the valves 3 8 and forced through the valves 5 10 into the common pressure-pipe 13, which conducts the mixture of gas and air to the container 14 and the service-main 15. If the pressure in the container 14 or the service-main 15 exceeds a given limit—when, for example, more gas is produced than is consumed—the valve 17 is opened by the excess pressure acting upon the membrane 56. The mixture of gas and air then passes from the container 14 through the pipe 16 into the branches 18 and 19 of the circulation-pipe. The gas-and-air mixture entering the branch 18 reaches the section 20 of the gas-supply pipe 4 and closes the non-return valve 7. In the same manner the mixture entering the branch 19 closes the

valve 12. The excess pressure, therefore, simultaneously closes the gas-supply pipe 4 and the air-supply conduit 9. The suction and forcing appliances 1 2 then suck through the two valves 3 and 8 a mixture of gas and air and force it through the valves 5 and 10 back into the common pressure-main 13 and into the container 14. No suction or forcing of gas and air therefore takes place until the pressure has again fallen in the container 14 or in the service-main 15, so that the valve 17 will close automatically. The non-return valves 7 and 12 are then able to open and gas and air will again be sucked in.

As the suction-valves for gas and air are closed simultaneously the mixing proportion originally decided upon is maintained when the circulation-pipe becomes operative. When an excess of pressure occurs, the admission of gas and air is prevented and the gas-and-air mixture is returned to the container 14 with the same composition as that with which it is withdrawn therefrom. A further important point is that the gas-and-air mixture is sucked through both the suction-valve 3 for the gas and the suction-valve 8 for the air. By this means the suction and forcing appliances are always required to perform the same work independently of whether they are used for the suction of one kind of gas or of a mixture, so that a strain upon these devices varying with the demands upon the service-main is prevented. By this means better working conditions and more efficient operation are obtained.

In the installation represented in Fig. 2 a common suction-chamber 27 is provided for the gas and air. The air-suction valve 8 is in this case arranged behind the gas-valve 3. The two valves 3 and 8 are arranged behind the common inlet-passage 28 to the suction-chamber 27 in such a manner that the gas and air permeate each other and become mingled before admission to the suction-chamber 27. As shown in Fig. 6, in which the two valves are represented on a larger scale, both the valves 3 and 8 are arranged in a common casing 29, the air-valve 8 being below the gas-valve 3. Between the two valves is situated a union 30 for the connection of the gas-supply pipe. In its lower part the casing 29 is provided with apertures 31, through which air is sucked into the suction apparatus during the suction operation. The obturating member 8 of the air-valve is displaceable upon the common rod 32 for both valves and may be submitted to the action of a spring 33 tending to apply it to the valve-seat 34.

As there is only a single suction-chamber, only a single pressure-valve 35 is provided. The circulation-conduit 16 18 connects the pressure-main 13 with the gas-supply pipe 4.

During the suction period in the suction and forcing apparatus the obturating members 3 and 8 are raised from their seats, so

that the gas conducted through the pipe 4 20 and the air entering through the openings 31 can reach the passage 28 and the suction-chamber 27, from which the mixture reaches the pressure-main 13 through the valve 35. A container or the like may be connected to the pressure-main or it may lead directly into the service-pipe. When an excess of pressure occurs in the pressure-main 13, the mixture of gas and air enters the branch pipe 16 and passes through the valve 17 into the pipe 18 and the length 20 of the gas-supply pipe. As soon as the mixture of gas and air reaches this length of pipe 20 on the one hand the non-return valve 7 is maintained closed by the excess pressure, thereby cutting off the supply of gas from the valve 3, while on the other hand the mixture of gas and air enters the chamber 36 between the two obturating members 3 and 8. The member 8 for cutting off the air-supply, which is mounted loosely upon the rod 32, is pressed upon its seat 34, so that the air entering through the apertures 31 cannot reach the gas-obturating member 3, and therefore no air will enter the suction and forcing apparatus during the suction period. When there is an excess of pressure in the pipe 13, when suction is produced in the suction and forcing apparatus only the valve 3 will be lifted, and through the opening so produced the gas-and-air mixture which has previously passed through the apparatus will be sucked out of the conduit 16 18. Consequently in this case when an excess of pressure occurs in the service-pipe both the gas and air supplies are cut off and the predetermined proportions of the mixture of the two kinds of gases are maintained as the apparatus sucks in the mixture of gas and air.

It is not absolutely necessary to connect the circulation-conduit 16 18 to the gas-main, Fig. 2, or to the gas and air conduit, Fig. 1. It may be arranged in the manner shown in Fig. 3, where it is not in communication with either of these conduits, but is still able to produce the obturation of the said conduits by means of an excess of pressure within it. In this case the valve-casing 29 is provided with a second union socket 37, to which the circulation-conduit 16 18 is connected. Within the casing 29 a special obturating member 38 is also provided and is under the influence of a spring 39. In this installation a non-return valve 24 is arranged in the branch 18 of the circulation-conduit. This valve opens in the direction of the suction and forcing apparatus and closes toward the valve.

When, owing to excess pressure in the service-pipe, the excess-pressure valve 17 is opened, the mixture of gas and air passes from the conduit 13 through the circulation-conduit 16 18, opening the valve 24, into the upper chamber 40 of the valve-casing 29, presses upon the obturating member 38 and maintains it in the closed position until the

normal pressure is re-established in the service-pipe. Owing to the fact that the obturating member 38 is maintained closed, the valves 3 and 8 are no longer influenced by the suction action in the apparatus 12, and neither gas nor air enters this apparatus. Only the mixture of gas and air previously produced is sucked in. Obviously the transmission of pressure to the circulation-conduit is here prevented during the forcing period of the apparatus by the provision of the valve 24, because during that forcing period the valve 24 is closed. This is of special value, because it obviates chattering of the valve 17. In this installation the air-obturating member 8 may be dispensed with, as shown in Fig. 7. The gas-supply pipe communicates with an annular passage 41, from which proceed radial openings 42, opening in the seat-face of the gas-obturating member 3. The radial arrangement of the gas-outlet passage 42 presents the advantage that a more intimate mixture of gas and air is produced.

In Fig. 4 an installation is illustrated in which a common suction and forcing apparatus for gas and air is provided and in which the circulation-conduit opens into the gas-conduit and into the air-supply conduit. The gas-supply conduit 4 20 and the air-supply conduit 9 21 are in this case connected to the inlet-valve casing 29. The branch 18 of the circulation-conduit is in communication with the gas-supply pipe 4 and the branch 19 with the air-supply pipe 21.

When there is no excess of pressure, the gas entering through the conduit 4 closes the valve 23^a, so that the passage of gas from the conduit 4 into the air-supply conduit 21 is prevented. During the suction period the gas enters the suction apparatus 12 through the valve 3 from the conduit 20, the air through the valve 8 from the conduit 21. The mixture of gas and air is forced into the pressure-main 13 through the valve 35.

When an excess of pressure occurs in the service-pipe 15 or in the container 14, it extends to the conduit 16 and opens the valve 17, so that the mixture of gas and air partly enters the conduit 19 and partly the conduit 18. By this means the non-return valve 12 in the air-supply pipe 9 and the non-return valve 7 in the gas-supply pipe 4 are closed. When the suction period is reached in the apparatus 12, a mixture of gas and air is sucked through the valves 8 and 3. The same cross-section is therefore available for the passage of the gas-and-air mixture as was before provided for the passage of the gas and the air. As soon as the excess of pressure ceases the valves 17 and 23^a again close and the valves 7 and 12 are opened by the suction action, so that gas and air are again sucked in.

When a pressure collector or container is provided for the reception of the mixture of gas and air, as shown in Fig. 5, the regulation

of the valve 17 of the circulation-conduit may be effected by the movable bell 45 of the said container, which when the predetermined quantity of the mixture is present cuts off a further supply. To this end a rod 46 may be fixed to the bell or dome 45 and provided with an inclined plane 47. Upon the rod 46 travels a roller 48, mounted upon the rod of the valve 17. When the bell 45 rises, the inclined plane 47 gradually approaches the roller 48. The roller 48, and with it the obturating member of the valve 17, is displaced in the direction of the arrow *b* against the action of the spring 49, and the valve 17 is thereby opened. It is then possible for gas-and-air mixture to pass from the container or from the pressure-main 13 through the conduit 16 into the conduit 18, the non-return valve 7 in the gas-supply pipe and the non-return valve 12 in the air-supply pipe are closed, and gas-and-air mixture is sucked through the valves 3 and 8. When the quantity of gas-and-air mixture has decreased by a predetermined amount, which is dependent upon the length of the inclined plane 27, so that the bell descends, the rod 46 releases the roller 48 and the valve 17 closes under the influence of the spring 49. As there is then no excess pressure to maintain the valves 7 and 12 closed, gas and air will again be sucked into the apparatus 12 during the suction period.

The closing of the air-suction conduit when excess pressure occurs in the service-pipe may also be produced, owing to the fact that the excess-pressure valve directly displaces an obturating member for the air-conduit. (See Fig. 8.) The obturating member 17 of the excess-pressure valve may be provided with a rod 55, carrying a membrane 56. A lever 53, articulated to a rod 54, is connected to the valve-rod 55, and by means of a rod 52 it is connected with the obturating member 50, pivoted upon the pin 51.

When excess of pressure occurs in the service-pipe, the gas-and-air mixture passes through the conduit 16 under the membrane 56, which owing to the excess pressure bulges upward and lifts the rod 55. By this means the obturating member 17 is lifted from its seat, so that gas-and-air mixture is able to enter the conduit 18. At the same time, however, the flap-valve 50 is rotated by the intermediary of the rods 53 and 52 in such a manner as to close the air-admission aperture. The gas-supply conduit is obturated by the closing of the non-return valve 7. In this arrangement it is essential that the connection between the excess-pressure valve and the air-obturating member 50 should be obtained in such a manner that the said obturating member 50 only closes the air-supply conduit upon the opening of the excess-pressure valve and return of the excess pressure, but remains open during the suction and forcing of the air.

In carrying the invention into practice suc-

tion and forcing valves of any suitable construction may be employed. The obturating members for the gas and air conduits may be of various kinds. The suction and forcing apparatus may be arranged either vertically or horizontally. They may have either one or two cylinders and be single or double acting and provided with valves positively operated by levers 43 44, these levers being actuated by twin cams 43^a 44^a, Fig. 4, or by valves controlled otherwise. Pumps with rotary pistons may also be employed as suction and forcing apparatus. The essential point is that in all cases upon the opening of the excess-pressure valve and return of the excess pressure both the closing of the gas-supply pipe and of the air-supply pipe shall be effected.

What I claim, and desire to secure by Letters Patent of the United States, is—

1. In an apparatus of the character described, the combination of a circulation-conduit, means for inducing circulation therein, a pressure-valve connected with said circulation-conduit and controllable by pressure therefrom, an air-inlet and a gas-inlet connected with said circulation-conduit, and means actuated by air-pressure, controlled by said pressure-valve for cutting off the supply of gas and the supply of air.

2. In an apparatus of the character described, the combination of pumping mechanism adapted to work at a constant rate of speed, means for supplying gas and air to said pumping mechanism to be admixed therein under pressure, a circulation-conduit, a pressure-controlled member connected with said circulation-conduit and adapted to open for the purpose of relieving excessive pressure of said admixture of gas and air, the opening of said pressure-controlled member being independent of the speed of said pumping mechanism, and valve mechanism for simultaneously checking the inflow of both gas and air when said pressure-controlled member is open.

3. In an apparatus of the character described, the combination of pumping mechanism, means for supplying gas and air thereto so as to admix the same, a circulation-conduit connected with said pumping mechanism, a pressure-controlled member for relieving excessive pressure of said admixture of gas and air, and automatic valves actuated by pressure of said admixture and controllable by said pressure-controlled member for shutting off the supply of both gas and air.

4. In an apparatus of the character described, the combination of pumping mechanism, means for supplying gas and air thereto so as to cause said air and gas to be admixed thereby, a circulation-conduit connected with said pumping mechanism, a pressure-controlled member connected with said circulation-conduit, for relieving the excess of pressure of the admixture of said gas and

air, and valve mechanism actuated directly by pressure of an admixture of gas and air and controllable by said pressure-controlled member for simultaneously shutting off the supply of gas and the supply of air.

5. In an apparatus of the character described, the combination of pumping mechanism, means for supplying air and gas thereto so as to admix the same, a valve controlling the air-supply, a circulation-conduit connected with said pumping mechanism and with said means for supplying said air and said gas thereto, said circulation-conduit being provided with a pressure-controlled member for relieving the excess of pressure of said admixture of gas and air, and valve mechanism connected with said circulation-conduit and controllable automatically by pressure of the admixture therein for closing said valve controlling said air-supply.

6. The combination of a container, pumping mechanism connected therewith for forcing thereinto an admixture of gas and air, a circulation-conduit connected with said container and with said pumping mechanism, a pressure-controlled member connected with said circulation-conduit and with said pumping mechanism for the purpose of permitting a portion of said admixture to flow under an excessive pressure from said container through said circulation-conduit to said pumping mechanism, the action of said pressure-controlled member being independent of the speed of said pumping mechanism, and a check-valve connected with said circulation-conduit and free to open in one direction only when said pressure-controlled member is actuated.

7. The combination of a container, pumping mechanism connected therewith for forcing thereinto an admixture of gas and air, a circulation-conduit connected with said container and with said pumping mechanism, a pressure-controlled member connected with said circulation-conduit and free to open by back pressure from said container when said back pressure reaches a predetermined limit, the opening of said pressure-controlled member being independent of the speed of said pumping mechanism, and a valve connected with said circulation-conduit and free to open in a direction leading toward said pumping mechanism when said pressure-controlled member is opened, said valve being normally closed.

8. The combination of pumping mechanism provided with inlet-valves to be opened and closed for admitting gas and air, a pressure-pipe connected with said pumping mechanism and adapted to receive therefrom an admixture of said gas and air, a circulation-conduit con-

nected with said pressure-pipe and with said pumping mechanism, and means controllable by excessive pressure of air and gas within said pressure-pipe for controlling the closure of said inlet-valves.

9. The combination of pumping mechanism provided with inlet-valves for admitting air and gas, said inlet-valves being controllable by pressure of an aeriform body, a pressure-pipe connected with said pumping mechanism and adapted to receive therefrom an admixture of said gas and air, a circulation-conduit connected with said pressure-pipe and said pumping mechanism, said circulation-conduit being in communication with said inlet-valves and adapted to direct an aeriform pressure against the same, and a pressure-valve connected with said circulation-conduit, said pressure-valve being normally closed but free to open when the pressure within said conduit exceeds a predetermined limit, so that pressure from said circulation-conduit may close said inlet-valves.

10. The combination of pumping mechanism provided with inlet-valves for admitting gas and air, said inlet-valves being controllable by pressure of an aeriform body, a pressure-pipe connected with said pumping mechanism and adapted to receive therefrom an admixture of said gas and air, a normally closed circulation-conduit connected with said pressure-pipe and with said pumping mechanism, said circulation-conduit being also in communication with said inlet-valves, and a pressure-controlled member connected with said circulation-conduit and actuated by pressure therefrom, for the joint purpose of opening said circulation-conduit and of allowing pressure from said circulation-conduit to close said inlet-valves.

11. The combination of pumping mechanism provided with valves, a pressure-pipe connected to said pumping mechanism and adapted to receive therefrom an admixture of gas and air, valve mechanism located intermediate of said pumping mechanism and said pressure-pipe to prevent retrogression of said admixture, a circulation-conduit connected with said pressure-pipe and said pumping mechanism, and a pressure-valve connected with said circulation-conduit, said pressure-valve being normally closed but free to open when the pressure within said circulation-conduit exceeds a certain predetermined limit.

In testimony whereof I have hereunto set my hand, in presence of two subscribing witnesses, this 19th day of June, 1903.

HEINRICH LOUIS KARGER.
